Primary Examiner—James M. Gandy*Assistant Examiner*—Robin V. Taylor*Attorney, Agent, or Firm*—Richard B. O'Planick; Lisa B. Riedesel[57] **CLAIM**

The ornamental design for a refuse container body, as shown and described.

DESCRIPTION

FIG. 1 is a top right front perspective view of a wheeled refuse container body showing our new design;

FIG. 2 is a front elevational view thereof;

FIG. 3 is a top plan view thereof;

FIG. 4 is a left side elevational view thereof; the right side elevational view being a mirror image;

FIG. 5 is a bottom plan view thereof; and,

FIG. 6 is a rear elevational view thereof.

The broken line showing of wheels is for illustrative purposes only and forms no part of the claimed design.
